INSTRUMENT FACE FOR GYROSCOPIC INSTRUMENTS

David E. Harding, 5128 Aldrich Ave. S.,
Minneapolis, Minn.

Filed Oct. 14, 1964, Ser. No. 82,168

Term of patent 14 years

(Cl. D52—6)

FIG 1

FIG 2

FIG 3

FIGURE 1 is a front elevational view of an instrument face for gyroscopic instruments, showing my new design.

FIGURE 2 is a perspective view thereof.

FIGURE 3 is a fragmentary sectional view of the face portion thereof.

The portions of the drawing in broken lines are for illustration purposes only.

I claim:

The ornamental design for an instrument face for gyroscopic instruments, as shown and described.
